(57) **CLAIM**

The ornamental design for a self-service terminal, as shown and described.

DESCRIPTION

FIG. 1 is a perspective view of a self-service terminal showing our design;

FIG. 2 is a left side view of the self-service terminal shown in FIG. 1;

FIG. 3 is a right side view of the self-service terminal shown in FIG. 1;

FIG. 4 is a front view of the self-service terminal shown in FIG. 1;

FIG. 5 is a back view of the self-service terminal shown in FIG. 1; and,

FIG. 6 is a top view of the self-service terminal shown in FIG. 1.

The broken lines represent portions of the self-service terminal that form no part of the claimed design. The bottom of the self-service terminal is flat and devoid of surface ornamentation, and is therefore not shown.
